PACKAGE OF RAZOR BLADES

Filed March 25, 1930

UNITED STATES PATENT OFFICE

JOHN C. SHERMAN, OF GORHAM, MAINE

PACKAGE OF RAZOR BLADES

Application filed March 25, 1930. Serial No. 438,804.

This invention relates to a package of safety razor blades particularly adapted for convenient use with a safety razor such as is described in my applications Serial No. 251,561, filed February 3, 1928, Serial No. 339,527, filed February 13, 1929, and Serial No. 401,402 filed October 22, 1929. The present application is a continuation in part of these copending applications.

- 10 An object of the package hereinafter described is to facilitate the changing of blades in a safety razor without touching the blade itself with the fingers. To this end a pair of small hooks or catches are provided on
- 15 a guard plate of the razor itself, the catches being adapted to pass through suitable apertures in the blade and to catch on the lower face of the blade. For the successful operation of such a razor in picking up a blade, it
- 20 is necessary to provide a suitable clearance beneath the apertures through which the catches are to extend so that the catches may project through the blade far enough to catch on the lower face. To this end the individual
- 25 blades are arranged in alternation with a series of spacing elements which are suitably perforated to provide the desired clearances. According to the invention, a suitable support may be provided for holding the blades
- 30 in convenient position to be picked up by the guard plate of the razor. The spacing elements may be made of suitable material adapted to enclose and protect the blades from the atmosphere.
- 35 For a more complete understanding of the invention, reference may be had to the description thereof which follows and to the drawing, of which,

Figure 1 is a perspective view of a support having a portion of a package of blades thereon.

Figure 2 is a perspective view of a spacing element.

Figure 3 is a section on the line 3—3 of Figure 1.

Figure 4 is a fragmentary section on the line 4—4 of Figure 1.

Figure 5 is a fragmentary section similar to Figure 4, showing a slightly modified form of spacing element.

Figure 6 is a perspective view of a complete package of blades.

Referring to the drawing in detail, the package may consist of a number of blades 10, each blade having a series of three apertures 11 therein which may, if desired, be connected by a slot 12, these apertures and slots being for the purpose of receiving portions of the razor itself adapted to hold the blade in position. The blades 10 are also provided with a pair of apertures 13 adapted to receive the catches on the guard plate of a razor such as is described in my copending applications hereinbefore referred to. Between each successive pair of blades I may provide a spacing element 20 which may be made of any substance suitable for the purpose such as wood fiber which is cheap and easily obtainable. Each spacing element is preferably indented on one or both of its faces, as at 21, the maximum thickness of the spacer being in the form of a narrow rim 22 which extends around the depressed portion 21 of the faces. For convenience in handling a finger tab 23 may be provided at an end of the spacer.

In order to provide suitable clearance beneath the perforations 13 so as to permit the hooks of the razor to pass freely through the perforations 13 and to catch on the under side of the blade 10, suitable perforations 24 may be provided in the spacer 20. These may be made of sufficient size to include also the two apertures 11 which are adjacent to the perforations 13, so that the entire package may be placed on a pair of supporting pins 25 which, in turn, may be mounted on a suitable platform 26. The recessed portions 21 pressed into the faces of the spacer are adapted to be sufficiently deep to receive a blade between successive spacers and to permit the outer rims 22 to rest against each other, as shown in Figure 4, thus protecting the edges of the blade from contact with the spacers and from exposure to the atmosphere. Where both faces of each spacer are indented, the depth of the recesses is preferably half the thickness of a blade, as shown in Figures 3, 4 and 5, so that when the rims 22 of successive spacers are in face to face contact, 100

the indented faces of the spacers abut the faces of the blade between them. This results in the enclosure of the cutting edges of the blades in compartments which are cut off 5 completely from the outside atmosphere. The clearance between the cutting edges of the blades and the spacers may be increased, if desired, by indenting more deeply the portions of the faces of the spacers 27 adjacent 10 to the rims 22, as shown at 27 in Figure 5. This more effectively protects the cutting edges of the blades from possible contact with individual fibers which might stick out from the surface of the spacer.

15 A suitable number of blades 10 with a sufficient number of spacers to enclose them separately may be assembled as shown in Figure 6, with a band 30 of paper or the like secured around the package. In order to prevent lateral displacement of the spacers upon 20 each other which might result in exposure of blades to the atmosphere, and to stiffen the package as a whole, I may provide a pair of members 31 which have hollow lower end 25 portions to take over the ends of the pins 25. These members may be thin metal tubes, as shown, are preferably of a length to extend through a package of blades and spacers from top to bottom. The upper end portions 30 of these members may be slightly enlarged so as to make a tight fit in the uppermost spacer and thus to retain the members in position. The pins 25 of the package holder may have reduced upper portions 32 with 35 shoulders 33 adapted to be engaged by the lower ends of the tubes 31. Thus the blades and spacers may be conveniently placed on a support by placing a package above the support with the lower ends of the tubes 31 resting 40 on the shoulders 33 of the supporting pins 25. Downward pressure on the package will cause the blades and spacers to slide from the tubes 31 to the pins 25. The tie element 30 may encircle the package between the tubes 45 31, as shown, so that it need not be removed until the package has been shifted from the tubes 31 to the pins 25. The tubes 31 and tie element 30 are then removed and thrown away, the spacers and blades thereupon being 50 ready to be removed one at a time as desired.

I claim:

1. A package of razor blades comprising a plurality of spacing elements and a blade 55 between each pair of successive elements, each said spacing element having a depressed area in a face thereof to receive a blade and a marginal rim in face-to-face engagement with the marginal rims of the adjacent spacers.
2. A package of safety razor blades comprising a plurality of blades, each having a pair of perforations therein adapted to cooperate with catches on a razor, and a spacing element between each pair of successive 60 blades, each said spacing element having per-

forations therethrough in line with said perforations in each blade, whereby a pair of uninterrupted holes extend through the package.

3. A package of safety razor blades comprising a plurality of blades each having a pair of perforations therethrough adapted to receive catch elements on a razor, and a spacing element between each pair of successive blades, said spacing element having a depressed area in a face thereof adapted to receive a blade, said spacing element also having a pair of apertures therein adapted to underlie the perforations in a blade. 75

4. A spacing element for a razor blade 80 package comprising a substantially rectangular flat member having an area indented in each face thereof to receive blades therein, said indented areas being surrounded by a thicker marginal rim, and a tab projecting from one corner of said rectangular member, said member also having a pair of perforations therethrough adapted to underlie perforations in a razor blade. 85

5. A package of razor blades comprising a plurality of perforated blades, a perforated spacing element between successive blades and on the top and bottom of the package, each said element having a rim portion thicker than the intermediate portion and in contact with the rim portions of the adjacent elements, a pair of tubes extending downwardly from the top to the bottom of said package through perforations in said blades and spacers, and a tie member encircling 90 said package. 95

6. A rectangular fibrous spacing element for a package of safety razor blades having a finger-tab projecting from a corner thereof.

7. A rectangular fibrous spacing element having a continuous rim portion of substantially uniform thickness about its periphery, and a central portion of lesser thickness, said element also having a finger-tab projecting 100 from said rim. 105

8. A package of razor blades, comprising a plurality of blades, spacing elements between successive blades and on the top and bottom of the package, and a pair of members extending from the top to the bottom 115 of the package through perforations in the blades and spacers, the lower end portion of each member being hollow.

9. A package of razor blades, comprising a plurality of blades, spacing elements between successive blades and on the top and bottom of the package, a pair of members extending from the top to the bottom of the package through perforations in the blades and spacers, each said member having a hollow lower end portion, and a tie element encircling said package and passing between 120 said members. 125

10. A package of perforated razor blades, comprising a plurality of alternating blades 130

and spacers in face to face engagement, each said spacer having a pair of perforations aligned with blade perforations and a continuous rim portion which is thicker than the intermediate portion and in contact with the rim portions of the spacers adjacent thereto, and a pair of members extending through said package in aligned perforations of said blades and spacers, said members each having a hollow lower end portion.

11. A package of razor blades comprising a plurality of spacing elements and a blade between each pair of elements, said spacing elements having shallow indentations on faces thereof bounded by rim portions adapted to engage each other when a blade is between the spacers, the portions of the spacers adjacent to the cutting edges of the blades being additionally indented to provide extra clearance between the cutting edges and the spacers.

12. A spacing element for a blade package, said element comprising a relatively thin central portion having surfaces to receive razor blades, and a relatively thick rim portion entirely surrounding the central portion and spaced from the cutting edges of blades in position against the faces of said central portion, said central portion having perforations in line with perforations of blades assembled therewith, said central portion also having depressed areas adjacent to the cutting edges of said blades to provide extra clearance from the cutting edges.

35 In testimony whereof I have affixed my signature.

JOHN C. SHERMAN.
